AUTOMATIC CIRCUIT BREAKER

Joseph Sachs, West Hartford, Conn.

Application January 3, 1936, Serial No. 57,389
Renewed April 20, 1937

15 Claims. (Cl. 200—116)

The invention relates particularly to a circuit breaker of the general type disclosed in my co-pending application for Automatic circuit breakers, Serial No. 57,388 filed January 3, 1936. In such a circuit breaker the circuit may be opened by the manipulation of a handle or other operating member, or may be opened automatically independently of the operating member upon the attainment of excess or other abnormal current conditions, or may be opened mechanically independently of the operating member and independently of the current conditions in the circuit. One of the objects of the invention is to provide a circuit breaker of this type wherein the means for mechanically opening the circuit independently of the operating member is controlled by the current responsive means and is supported independently of the operating member and independently of certain other parts as will presently be set forth.

While the invention is applicable in a number of ways it is particularly applicable to an automatic circuit breaker of the multi-polar type wherein there are independently acting circuit breaker mechanisms in two or more legs of the circuit; and it is a further object of the invention to provide in a circuit breaker of this type improved means whereby the mechanism in one leg of the circuit serves upon automatic opening to effect the opening of the mechanism in each other leg of the circuit.

A further object of the invention is to provide a circuit breaker having a plurality of circuit breaking units for the different legs of the circuit, and wherein the several units are detachable and replaceable independently of each other.

Further objects of the invention will be apparent from the following specification and claims:

40 A multi-polar circuit breaker has been shown in the drawings as illustrating the invention, but it will be understood that the invention in its broader aspects is not so limited. The particular form of multi-polar circuit breaker shown is only 45 one of several possible embodiments of the more specific phases of the invention and is to be regarded as merely representative or typical. The drawings are not to be relied upon as defining or 50 limiting the scope of the invention, the claims forming a part of this specification being relied upon for that purpose.

Of the drawings:

Fig. 1 is a front view of an automatic circuit breaker embodying the invention, the enclosing casing being omitted. In this view the front

cover and vented insulating block of one of the units are omitted.

Fig. 2 is a bottom view of the parts shown in Fig. 1, this view showing a portion of the enclosing casing in transverse section.

Fig. 3 is a longitudinal sectional view taken along the line 3—3 of Fig. 2 and showing the movable parts in their closed-circuit positions.

Fig. 4 is a longitudinal sectional view taken along the line 4—4 of Fig. 2 and showing the contact member of one circuit breaker mechanism in an intermediate position, it being assumed that the said member has been automatically released and is moving toward its open-circuit position.

Fig. 5 is a view similar to Fig. 4 but showing the contact member in its full open-circuit position and also showing the connecting parts in the positions which they occupy when the operating member is held in its closed-circuit position.

Fig. 6 is a view similar to Fig. 5 but showing the connecting parts and the operating member in their open-circuit positions.

The circuit breaker as shown in the drawings comprises three circuit opening and closing mechanisms connectible in three legs of a circuit. It will be understood, however, that I do not limit myself to this exact number of mechanisms and that only two or more than three mechanisms may be provided when required. In fact, as concerns certain phases of the invention only one mechanism is necessary. The three mechanisms shown are similar in construction, and in conjunction with the common operating mechanism each may be regarded as embodying the invention in its broader aspects. Each of the said mechanisms is in many respects similar to that shown and described in my patent for Automatic circuit breaker No. 2,020,333 dated November 12, 1935. While a mechanism of the particular type shown in the said patent is well suited for use in a circuit breaker embodying the present invention, I do not necessarily so limit myself.

I prefer and have shown in the drawings a circuit breaker wherein each circuit breaker mechanism is a separate self-contained unit. The several units are readily detachably mounted on a suitable support which may be a metal plate 1. As shown this plate 1 is suitably secured to the rear wall of an enclosing cabinet 2 having an openable front cover 3.

A description of one of the circuit breaker mechanisms or units will suffice for all, and the following description will relate chiefly to the mechanism at the right as viewed in Figs. 1—55

and 2. In the drawings the letter *a* will be added to the reference numbers to designate corresponding parts in the unit at the center, and the letter *b* will be added to the reference numbers 5 to designate the corresponding parts of the unit at the left.

Each unit has a main insulating base 4 which carries all of the other parts of the unit. Fitting the base 4 at the front thereof is an insulating cover 5. The base 4 has a mechanism containing recess 6 therein, which is substantially closed at all four sides and at the bottom. The bottom wall of the recess is in the form of a removable insulating block 6' which is vented to permit the 10 escape of arc formed gases as explained in my said patent. The block at the right is omitted in Fig. 1. The front cover has a recess open at the bottom into which certain parts of the mechanism project. When the two parts 4 and 5 are 15 assembled as shown, the recesses register and provide an interior chamber which contains all of the operative parts of the circuit breaker mechanism other than the intermediate operating member.

25 Carried by the base 4 near the front thereof and adjacent the recess 6 are two forward projecting parallel metallic plates 7, 7 which are held in place by means of screws 8, 8 embedded in the walls of the base. The plates 7, 7 are 30 provided with integral rearward extending portions 9, 9. Carried by the said rearward extensions 9, 9 and extending transversely between them is a pivot pin 10.

The circuit breaker mechanism has a contact 35 carrying member which is mounted on the pivot pin 10 and includes two parallel plates 11, 11 spaced apart transversely and suitably connected together to move as a unit. These plates have aligned bearing apertures through which 40 the pivot pin extends. Suitable spacing washers, not shown, hold the plates in proper spaced relationship to the supporting plate extensions 9, 9.

The two plates 11, 11 serve to carry the main 45 movable circuit breaker contacts 12 and 13 of the circuit breaker which are arranged in tandem, being spaced apart in the direction of movement, that is, circumferentially. Preferably and as will be clearly apparent from an examination of Figs. 1 and 2, each movable contact 12 and 13 extends 50 from one to the other of the two plates 11, 11 and is in direct engagement with both of them. Each of the said plates 11 is provided with a hole and a notch, as shown in Fig. 3, adapted to receive similarly shaped lateral projections on the corresponding contact. When the said projections on the contacts are entered in the said holes and notches of the two plates, the contacts are firmly held in proper pre-determined relationship. It will be observed that, by reason of the tandem 55 arrangement of the contacts, the two plates 11, 11 are much closer together than would otherwise be possible.

The two plates 11, 11 are additionally connected and held in spaced relation by means of 60 transverse insulating members 14 and 15, structurally separate from the plates and held in proper relationship by means of the tie rods or rivets 16 and 17 extending through suitable holes. It will be apparent that the insulating members 65 14 and 15 extend transversely from the plate to plate and that the movable contact 12 extends through the space between the two members. The member 15 engages with both movable contacts and extends circumferentially from one to 70 the other. The two plates 11 together with the

parts which mechanically connect them and together with the contacts which they carry, will for the sake of convenience be herein referred to collectively as a "contact member."

The two movable contacts 12 and 13 are electrically connected with each other, this electrical connection preferably being through an electro-responsive device which is carried by and is bodily movable with the contact member. By preference and as shown, this electro-responsive 10 device is a bi-metallic thermostatic strip 18 mechanically and electrically connected directly with one of the contacts, as for instance the contact 12. The strip 18 is provided at its projecting, 15 end with an aperture 19 which enables the strip to serve as a latch as will be presently explained.

In order to complete the electrical connection between the two contacts 12 and 13 there is provided a suitable flexing or flexible connection 20 between the strip 18 and the contact 13. This 20 flexing connection is connected to the strip by means of a yoke 21 and is sufficiently flexible to permit the bi-metallic strip 18 to freely deflect or bend under the influence of heat.

Carried by the insulating base 4 are two substantially stationary main contacts 22 and 23 which are connected with the said base by means of more or less resilient conducting straps 24 and 25, which may be supplemented by flexible conductors 26 and 27. These stationary contacts 22 30 and 23 are so positioned and arranged that they can be firmly engaged respectively by the two movable contacts 12 and 13 as clearly shown in Fig. 3. The resilient strap 24 and the conductors 35 26 are carried by the base 4 and are connected with a wire terminal 28. The resilient strap 26 and the conductors 27 are carried by the base and are connected with a wire terminal 29.

From the foregoing description it will be apparent that pivotal movement of the contact 40 member serves to bring the movable contacts 12 and 13 into or out of engagement with the respective stationary contacts 22 and 23 to make or break the circuit. When the parts are in the contact engaging position, as shown in Fig. 3 45 electrical connection is established between the terminal 28 and the terminal 29. A suitable spring 30 is provided for biasing the contact member in the contact disengaging or circuit-opening direction.

50 For operating the circuit breaker mechanism there is provided a member 31 which will be designated as an "intermediate" member. This intermediate member is mounted on a pin 32 extending transversely between the supporting 55 plates 7, 7. The intermediate member projects through an opening in the front wall of the front cover 5, the opening being of sufficient length to permit the necessary movement.

Interposed in the operative connection between 60 the intermediate member 31 and the contact member is an actuating member or actuator 33 of bell-crank form. The actuator is normally engaged by the thermostatic strip or latch 18, and the actuator is so positioned and connected that 65 a portion of the stress of actuation is transmitted directly from the actuator to the contact member independently of the thermostatic latch. The actuator 33 is pivotally mounted on a pin 34 extending transversely between the two side plates 70 11, 11 and is held by two spacing bushings. The actuator is provided with a pointed end which, at normal temperatures, is entered in the aperture 19 in the thermostatic latch 18. With the parts 75 in the relative positions shown in Figs. 3, 5 and 75

6, the actuator and the contact member are positively connected to move in unison.

The intermediate member 31 is connected with the actuator 33 by means of a pivoted link 35.

5 The link 35 does not move into toggling relationship with the intermediate member 31, this being prevented by a stop 31' which engages the member 31.

When there are two or more circuit breaker units as shown, they are mounted side by side on the common support 1 and their intermediate members 31, 31^a and 31^b are connected together for movement in unison. The several intermediate members will be referred to collectively as 15 intermediate means.

For moving the intermediate means and thereby moving the contact members to open or close the circuit, there is provided a handle or operating member 36. As shown, this operating member 20 36 is rigidly secured to a transverse shaft 37 which is mounted in suitable bearing apertures in sheet metal brackets 38, 38, preferably formed integrally with the sheet metal supporting plate 1. The operating member 36 is so positioned that its 25 forward portion projects through a suitable aperture in the front cover 3 of the cabinet. A spring 39 serves to bias the operating member for movement toward its open-circuit position as shown in Fig. 6.

30 A normally operative mechanical connection is interposed between the operating member 36 and the intermediate means 31, 31^a and 31^b, this operative connection being adapted to be rendered ineffective so as to permit the intermediate means 35 and the contact members connected therewith to move to their open-circuit positions independently of the operating member. This operative connection preferably is of the triple toggle type. As shown, one link consists of a lever 40 rigidly 40 secured to the shaft 37. Another link consists of a yoke 41 having a plurality of arms which are detachably pivoted to the several intermediate members 31, 31^a and 31^b, as for instance by means of pivot studs 42, 42^a and 42^b, which may be regarded as constituting a part of the link 41. The yoke 41 has a downward extending arm 41'. A link 43 is pivotally connected with the arm 41' at 44 and is pivotally connected to the arm 40 at 45. A spring 46 tends to hold the two links 41 50 and 43 in their toggle or locking relationship as shown in Fig. 3.

It will be observed that when the parts are in the closed-circuit positions shown in Fig. 3, the pivotal axes at 44 and 45 are behind a straight line connecting the pivotal axes at 42 and 37, the triple toggle linkage thus resisting the tendency of the intermediate members and the contact members to move to their open-circuit positions under the influence of the springs 30.

60 The toggle action also resists the tendency of the handle or operating member 36 to move to its open-circuit position under the influence of gravity and under the influence of the spring 39.

The circuit can be broken in all of the legs 65 thereof by manually moving the handle or operating member 36 from its upper position as shown in Fig. 3 to its lower position as shown in Fig. 6; and the circuit can be closed by moving the operating member from the position shown in Fig. 6 to the position shown in Fig. 3. During such opening and closing movements the two links 41 and 43 remain in their toggle or locking relationship and the bi-metallic latches 18 remain in engagement with the actuators 33.

75 As already explained, the bi-metallic strip 18 is

electrically connected between the contacts 12 and 13. It is adapted to be deflected rearward or radially outward upon the passage of excess current therethrough, with the result that the apertured portion 19 is disengaged from the end of the actuator 33. This leaves the actuator free to turn, and the actuator therefore no longer holds the contact member in the closed-circuit position against the influence of the spring. The contact member therefore moves toward its open-circuit position as shown in Fig. 4. It will be observed that this automatic circuit-opening movement of each contact member takes place independently of each other contact member and also independently of the intermediate member and of the 15 operating member.

In accordance with the invention, I provide a means which is dependent upon the operation of any one of the electroresponsive devices and which thereupon serves to release the holding 20 means for the intermediate means and thus permit the intermediate means and each remaining contact member to move to their open-circuit positions. The last said means may be varied as 25 to mechanical structure but as shown it is constructed to be actuated by any one of the contact members when such member approaches its open-circuit position. The said means includes a transverse bar 47 which is positioned at the front 30 of the circuit breaker units and immediately behind the pivotal connection at 44 between the links 41 and 43. The bar 47 is supported and guided for forward and backward movement by means of arms 48, 48 loosely pivoted on the shaft 37. Carried by the front cover 5, of each circuit 35 breaker mechanism is a movable slide 49. Each slide 49 is immediately behind the transverse bar 47 and is guided for forward and backward movement in a suitable aperture in the front cover. Each slide 49 is so positioned as to be adapted to 40 be engaged by a suitable transverse rod 50 extending between the two side plates 11, 11 of the corresponding contact member.

When any one of the circuit breaker mechanisms, as for instance the mechanism at the right, 45 is automatically operated by reason of abnormal current conditions, the contact member thereof moves in the clockwise direction and the cross bar 50 engages the corresponding slide 49 as shown in Fig. 4. Continued movement of the contact member to its complete open-circuit position causes the slide 49 to be moved forward to the position shown in Fig. 5 and the slide 49 in so moving moves the cross bar 47 to the position 55 shown in the same figure. Inasmuch as the cross bar 47 is behind the pivotal connection at 44, the pivotal connection is moved forward in opposition to the spring 46. The breaking of the toggle relationship of the links 41 and 43 permits the intermediate members 31, 31^a and 31^b and the remaining contact members to move to their open-circuit positions under the influence of the remaining springs biasing such contact members. It will be observed that the automatic operation 60 of one circuit breaker mechanism thus serves to automatically cause the operation of the other circuit breaker mechanisms.

The movement of the intermediate member 31 to its open-circuit position as shown in Fig. 5 restores the actuator 33 to its normal latching relationship with the latch 18 and relatching automatically occurs.

It will be observed that the automatic operation of all of the circuit breaker mechanisms occurs independently of the handle or operating 75

member 36. This will be clear from an inspection of Fig. 5, it being assumed that the operating member 36 has been held in its closed-circuit position as there shown. However, if the operating member is not held in its closed-circuit position, or if it be first held and then released, the operating member will move to its open-circuit position as shown in Fig. 6 under the influence of gravity and under the influence of the spring 39. This 10 movement of the operating member to its open-circuit position permits the links 41 and 43 to again assume their locking relationship under the influence of the spring 46 as shown in Fig. 6. As already stated, the circuit can then be closed 15 by moving the operating member 36 upward and thus moving all of the parts from the positions shown in Fig. 6 to the positions shown in Fig. 3. If the handle be held in its closed-circuit position and if all of the electro-responsive devices 20 operate simultaneously, there would then be nothing to move the intermediate members out of the position shown in Figs. 3 and 4. However, upon release of the handle, the handle spring 39, supplemented by gravity, would move the several 25 parts to the relative positions shown in Fig. 6 and relatching would thereupon occur.

While I do not necessarily so limit myself, I prefer to construct the several circuit breaker mechanisms as separate detachable units such as 30 have already been described. Each of the units is detachably connected with the rear supporting plate 1 by means of screws such as 51^a, 51^b and 51^c, 51^d. As already stated, the intermediate members of the several mechanisms are detach- 35 ably connected with the operating mechanisms, as for instance by means of the studs 42, 42^a and 42^b. It will therefore be apparent that any one of the units can be readily removed independently of any other unit for inspection, adjustment, re- 40 pair or replacement. By providing one or more spare units the circuit breaker as a whole can be kept in service even though some difficulty may arise in connection with one or more units. The invention in its broader aspects is not necessarily 45 limited to a plurality of independently movable contact members. It will be observed that there is associated with each movable contact member a movable operating member and also a movable intermediate member. Two separate mechanical 50 connections are provided, one between the contact member and the intermediate member and one between the intermediate member and the operating member. Each of these mechanical connections is adapted to be released or rendered to 55 be ineffective and one of them is adapted to be so released or rendered ineffective electro-responsively upon the attainment of abnormal current conditions in the circuit. In accordance with one phase of the present invention there is provided 60 a means supported independently of any of the aforesaid members and actuated upon the operation of the electro-responsive device in one mechanical connection and serving when so actuated to mechanically engage the other mechanical 65 connection to render it ineffective. Specifically and as illustrated, the said independently supported means includes the slide 49 and the trans- 70 verse rod 50 with its supporting arms 48, 48.

As concerns the feature last above described, a 70 circuit breaker embodying the present invention is readily distinguishable from a circuit breaker embodying the invention set forth in my co-pending application Serial No. 57,388. In the structure of the co-pending application the mechanical 75 connection between the operating member and

the intermediate or actuating member is released or rendered ineffective by its own biasing spring as soon as the corresponding electro-responsive device operates; but in the present structure the connection between the operating member 36 and the intermediate member 31 is not released by spring action but on the contrary is released by reason of the independently supported ele- 5 ments 49 and 50 as already explained.

What I claim is:

1. In an automatic circuit breaker, the combination of a movable operating member, a movable intermediate member, a movable contact member, a mechanical connection normally operative to enable the intermediate member to move the contact member to open or close the circuit and adapted to be rendered ineffective so as to permit the contact member to move to its open-circuit position independently of the intermediate member, a second mechanical connection normally operative to enable the operating member to move the intermediate member and adapted to be rendered ineffective so as to permit the intermediate member to move to its open-circuit position independently of the operating member, one of the 20 said mechanical connections including an electro-responsive device which automatically renders it ineffective upon the attainment of abnormal current conditions in the circuit, and means supported independently of any of the aforesaid 30 members and actuated upon the operation of the electro-responsive device in one mechanical connection and serving when so actuated to mechanically engage the other mechanical connection to render it ineffective. 35

2. In an automatic circuit breaker, the combination of a movable operating member, a movable intermediate member, a movable contact member biased toward its open-circuit position, a mechanical connection normally operative to 40 enable the intermediate member to move the contact member to open or close the circuit which mechanical connection includes an electro-re- 45 sponsive device automatically releasable upon the attainment of abnormal current conditions in the circuit to permit independent circuit-opening movement of the contact member, a normally operative mechanical connection between the operating member and the intermediate member adapted to be rendered ineffective so as to permit the intermediate member and the contact mem- 50 ber to move to their open-circuit positions independently of the operating member, and means supported independently of any of the aforesaid members and actuated upon the operation of the 55 electro-responsive device in the first said mechanical connection and serving when so actuated to mechanically engage the second said mechanical connection to render it ineffective.

3. In an automatic circuit breaker, the combination of a movable operating member, a movable intermediate member, a movable contact member biased toward its open-circuit position, a mechanical connection normally operative to enable the intermediate member to move the 65 contact member to open or close the circuit which mechanical connection includes an electro-re- 70 sponsive device automatically releasable upon the attainment of abnormal current conditions in the circuit to permit independent circuit-opening movement of the contact member, a normally operative mechanical connection between the operating member and the intermediate member and adapted to be rendered ineffective so as to permit the intermediate member and the contact mem- 75 ber to move to their open-circuit positions independently of the operating member, and means supported independently of any of the aforesaid members and actuated upon the operation of the electro-responsive device in the first said mechanical connection and serving when so actuated to mechanically engage the second said mechanical connection to render it ineffective.

ber to move to their open-circuit positions independently of the operating member, means supported independently of any of the aforesaid members and actuated upon the operation of the 5 electro-responsive device in the first said mechanical connection and serving when so actuated to mechanically engage the second said mechanical connection to render it ineffective, and means automatically operable to move the intermediate 10 member to its open-circuit position upon the rendering ineffective of the second said mechanical connection.

4. In an automatic circuit breaker, the combination of a movable operating member biased 15 toward its open-circuit position, a movable intermediate member, a movable contact member biased toward its open-circuit position, a mechanical connection normally operative to enable the intermediate member to move the contact member to open or close the circuit which 20 mechanical connection includes an electro-responsive device automatically releasable upon the attainment of abnormal current conditions in the circuit to permit independent circuit-opening movement of the contact member, two toggle links normally in toggle relationship and mechanically connecting the operating member with the intermediate member to enable the former to move the latter, the said two links being also 25 normally in toggle relationship with the operating member so that the latter is normally held in its closed-circuit position, and means supported independently of any of the said members and actuated upon the operation of the said electro- 30 responsive device for moving the said two links out of toggle relation with each other to enable the actuating member to move to its open-circuit position independently of the operating member and also to enable the operating member to automatically move to its open-circuit position. 35

5. In an automatic circuit breaker, the combination of a movable intermediate means, a plurality of independently movable contact members each biased toward its open-circuit position, the 40 said contact members having contacts respectively connectible in different legs of the circuit, a plurality of mechanical connections normally operative to enable the intermediate means to move the several contact members to open or 45 close the circuit each of which mechanical connections includes an electro-responsive device automatically releasable upon the attainment of abnormal current conditions in the corresponding leg of the circuit to permit independent circuit-opening movement of the corresponding contact member, a device normally operative to hold the intermediate means in its closed-circuit 50 position but adapted to be rendered ineffective so as to permit the intermediate means and the several contact members to move to their open-circuit positions, and means actuated upon the 55 operation of the electro-responsive device in any one of the said mechanical connections and serving when so actuated to mechanically engage the said holding device to render it ineffective, the last said means being supported independently of the holding device and also independently of either the intermediate means or the contact members. 60

70 6. In an automatic circuit breaker, the combination of a movable operating member, a movable intermediate means normally operatively connected with the operating member, a plurality of independently movable contact members biased 65 toward their open-circuit positions, a plurality

of mechanical connections normally operative to enable the intermediate means to move the respective contact members to open or close the circuit, each mechanical connection including an electro-responsively controlled device automatically releasable upon the attainment of abnormal current conditions in the circuit to permit automatic circuit-opening movement of the corresponding contact member independently of the intermediate means and independently of any other contact member, a releasable means 5 separate from the said mechanical connections with the contact members for normally holding the intermediate means in its closed-circuit position, and means dependent upon the operation 10 of the electro-responsively controlled device associated with any one of the said contact members and serving to release the said holding means and thus permit the intermediate means and each remaining contact member to move to their open- 15 circuit positions. 20

7. In an automatic circuit breaker, the combination of a movable operating member, a movable intermediate means normally operatively connected with the operating member, a plurality of independently movable contact members biased toward their open-circuit positions, a plurality of mechanical connections normally operative to enable the intermediate means to move the respective contact members to open or close the circuit, each mechanical connection including an electro-responsively controlled device automatically releasable upon the attainment of abnormal current conditions in the circuit to permit automatic circuit-opening movement of the corresponding contact member independently of the intermediate means and independently of any other contact member, a releasable means 25 separate from the said mechanical connections with the contact members for normally holding the intermediate means in its closed-circuit position, and means dependent upon the operation 30 of the electro-responsively controlled device associated with any one of the said contact members and serving to release the said holding means and thus permit the intermediate means and each remaining contact member to move to their open- 35 circuit positions. 40

8. In an automatic circuit breaker, the combination of a movable operating member, a movable intermediate means, a plurality of independently movable contact members biased toward their open-circuit positions, a plurality of mechanical connections normally operative to enable the intermediate means to move the respective contact members to open or close the circuit, each mechanical connection including an electro-responsively controlled device automatically releasable upon the attainment of abnormal current conditions in the circuit to permit automatic circuit-opening movement of the corresponding contact member independently of the intermediate means and independently of any other contact member, a releasable means operatively connecting the operating member with the intermediate means, and means dependent upon the operation of the electro-responsively controlled device associated with any one of the said contact members and serving to release the last said releasable means and thus permit the intermediate means and each remaining contact member to move to their open-circuit positions independently of the operating member. 55 60

9. In an automatic circuit breaker, the combination of a movable operating member biased 65

support and having its intermediate member detachably connected with the operative connection so that each unit may be detached or attached independently of each other unit, and
5 means dependent upon the operation of the electro-responsively controlled device of any one of the units and serving to release the said operative connection and permit the intermediate members and each remaining contact member to
10 move to their open-circuit positions.

15. In an automatic circuit breaker comprising a stationary support, a movable operating member and a releasable operative connection movable by the operating member, the combination
15 with the said support, member and connection of a plurality of separate circuit breaker units, each comprising a movable intermediate member, a movable contact member biased toward its open-circuit position, and a mechanical connection normally operative to enable the intermedi-

ate member to move the contact member which mechanical connection includes an electro-responsively controlled device automatically releasable upon the attainment of abnormal current conditions in the circuit to permit circuit-opening movement of the contact member independently of the intermediate member, each of the said units being detachably mounted on the support and having its intermediate member detachably connected with the operative connection so that each unit may be detached or attached independently of each other unit, and means adapted to be actuated by any one of the contact members upon independent circuit-opening movement thereof and serving upon being so
15 actuated to release the said operative connection and permit the intermediate members and each remaining contact member to move to their open-circuit positions.

JOSEPH SACHS. 20
